Primary Examiner — Patricia A Palasik(74) *Attorney, Agent, or Firm* — Renner, Otto, Boisselle & Sklar, LLP(57) **CLAIM**

The ornamental design for a robot, as shown and described.

DESCRIPTION

FIG. 1 is a front elevation view of a first embodiment of a robot showing our new design;

FIG. 2 is a bottom plan view thereof;

FIG. 3 is a top plan view thereof;

FIG. 4 is a rear elevation view thereof;

FIG. 5 is a top, left, front, perspective view thereof;

FIG. 6 is a left side elevation view thereof; and,

FIG. 7 is a right side elevation view thereof.

The broken line showing in FIGS. 1-7 is for the purpose of illustrating portions of the robot which form no part of the claimed design.

1 Claim, 7 Drawing Sheets(56)
